UNITED STATES PATENT OFFICE.

ALFRED WILKIN, OF TOLEDO, OHIO.

SELF-ACTING WATER-ELEVATOR.

SPECIFICATION forming part of Letters Patent No. 341,617, dated May 11, 1886.

Application filed March 8, 1886. Serial No. 194,421. (No model.)

To all whom it may concern:

Be it known that I, ALFRED WILKIN, of Toledo, in the county of Lucas and State of Ohio, have invented certain new and useful 5 Improvements in Self-Acting Water-Elevators; and I do hereby declare the following to be a full, clear, and exact description of the invention, such as will enable others skilled in the art to which it appertains to make and 10 use the same.

My invention relates to an improvement in self-acting water-elevators.

The object is to provide means for keeping a constant supply of water in an elevated 15 tank or reservoir by the employment of waste steam from a locomotive or other engine while receiving a supply of water from the tank or reservoir.

With this end in view my invention consists 20 in certain features of construction and combinations of parts, as will be hereinafter described, and pointed out in the claims.

In the accompanying drawings, Figure 1 is a view of the elevator and tank, partly in section, with engine in position to receive a supply 25 of water therefrom. Fig. 2 is an end view of the elevator, and Fig. 3 is a bottom plan view of the air-escape valve.

C represents a water tank or reservoir located 30 at a suitable height to supply water by gravity alone to the tender of a locomotive-engine, or to the boilers of other engines, or to give sufficient head for other purposes than supplying steam-boilers.

35 A represents a lower vacuum-chamber, and B an upper vacuum-chamber, the latter being located above the tank or reservoir. The vacuum-chambers A and B are conveniently oblong cylindrical chambers, similar in shape 40 to an ordinary locomotive-boiler. The internal construction and arrangement of the two chambers are essentially the same; but the upper chamber is preferably somewhat larger than the lower, for reasons which will 45 hereinafter appear. An inlet or feed pipe, a, provided with a check-valve, a', opening upwardly, leads from the chamber A to the well or other natural water-supply, the surface of which must not be at a greater depth below 50 the chamber A than the height of a column of water which the weight of the atmosphere will sustain. A pipe, D, leads from the base of the

chamber A to the base of the chamber B, and is provided with a check-valve, d, opening upwardly. A discharge-pipe, E, leads from the 55 base of the chamber B to the tank or reservoir C, and is provided with a weighted valve, e, gaged to open whenever the pressure of air is admitted on the water within the chamber B.

Each chamber A and B is provided with an 60 air-escape and air-inlet valve, F, balanced by a suitable weight, f, which admits of its opening freely when the vacuum formed within the chamber is satisfied.

To positively open the valve F when the 65 water reaches a proper height in the chamber, I provide a float, G, attached to the lower end of a lever-arm, g, the upper end of the said arm g being pivotally secured on a pin or bolt, h, extending across the opening beneath the 70 valve F. On the same pin or bolt, h, is also mounted or secured the cam-disk H, which, when the float and valve are depressed, is adapted to rest with its flattened side beneath the valve and in close proximity 75 thereto. The upper end of the arm g is preferably forked, as shown in Fig. 3, the cam-disk H being located partially between its branches. Two pairs of pins or stops, D', on the faces of the disk H are adapted 80 to engage the arm g at the proper step of its rise or fall and cause the cam-disk to rotate, thereby either opening valve F or allowing it to close, as the case may be. The corresponding ends of the vacuum-chambers are connected by a steam-inlet pipe, K, which preferably 85 opens into the chambers at about the centers of their ends.

Within the vacuum-chambers A and B, directly opposite the discharge-nozzles k' of the 90 steam-pipe K, are located funnel-shaped deflectors L and l, the larger, L, being located with its apex near the nozzle k, and the latter with its apex at the center of the mouth of the larger. There is also a small opening, l', at 95 the apex of each deflector. The deflectors serve to scatter the steam as it issues from the nozzle of the steam-pipe, and cause it to rapidly expel the air from every part of the vacuum-chamber. The steam-pipe K is provided 100 with a two-way cock, M, and a flexible pipe, N, leads from a nipple, m, near the cock M, to a steam-supply on an engine or boiler.

In the accompanying drawings a locomo-

tive is represented as taking water from the tank C, and furnishing steam to the vacuum-chamber through the pipe N.

The operation is as follows: Suppose the two vacuum-chambers to be empty and the valves F slightly open, which is their normal condition. The steam from the engine is first turned into the chamber A, and the air driven out through its escape-valve F. The steam is then turned into the chamber B by means of the cock M, and cut off from the chamber A. The air is expelled from the chamber B through its valve F, and the steam then cut off. As the steam in the chamber A condenses, a vacuum is formed, and the pressure on the outside of the valves F causes them to fall into a closed position, and the water rushes up through the pipe a and fills the chamber up to the point where the valve F is opened by the float and air-pressure admitted, the balance-weight on the valve F holding it open after air is admitted. The steam in the chamber B being now condensed, a vacuum is formed, and the water rushes from the chamber A into the chamber B until the valve F is opened and air-pressure admitted, when the discharge-valve in the pipe leading to the tank or reservoir C is opened by the pressure of water and air thereon, and the water escapes from the chamber B into the tank C. By making the upper chamber, B, somewhat larger than the chamber A the vacuum formed in B will insure the elevation of all the water from A, and freezing will be thereby guarded against.

It will be observed that there is no steam-pressure exerted in driving the water to the required elevation, but only in expelling air from the vacuum-chambers—an operation which is quickly and effectually accomplished at a very slight expenditure of steam.

It is evident that three or more vacuum-chambers might be employed instead of two, and that various other forms of vacuum-chambers, tanks, and pipe-connections might be resorted to without departing from the spirit and scope of my invention; hence I do not wish to limit myself strictly to the construction herein set forth; but,

Having fully described my invention, what I claim as new, and desire to secure by Letters Patent, is—

1. In a self-acting water-elevator, the combination, with the lower vacuum-chamber and the upper vacuum-chamber connected therewith, of a tank located below the upper vacuum-chamber and adapted to receive the water therefrom.

2. The combination, with the lower vacuum-chamber, the upper vacuum-chamber, a water-pipe connecting said chambers, and pipes for supplying steam thereto, of a tank located below the upper vacuum-chamber and adapted to receive the water therefrom, substantially as set forth.

3. The combination, with a vacuum-chamber and a pipe adapted to conduct steam into the chamber to form the vacuum, of a larger and a smaller deflector, constructed and located substantially as described, adapted to scatter the steam as it enters the chamber, substantially as set forth.

4. The combination, with a vacuum-chamber provided with an air-escape opening, of a counterbalanced valve adapted to rest in a normally-open adjustment when the vacuum is satisfied and a float adapted to positively open the valve and admit air into the vacuum, substantially as set forth.

5. The combination, with a chamber provided with an air-escape opening, of the counterbalanced valve adapted to close the air-escape opening and the cam and cam-operating lever adapted to automatically open the valve as the water reaches the desired height in the chamber, substantially as set forth.

6. The combination, with the lower vacuum-chamber and the upper vacuum-chamber connected therewith, of the water-escape opening leading from the upper vacuum-chamber to the tank and the weighted valve for closing the said opening, substantially as set forth.

7. The combination, with the two vacuum-chambers, of the steam-pipe connecting their ends, a steam-supply pipe adapted to conduct steam from a boiler to the said connecting pipe, and a two-way cock adapted to open and close the pipe leading to the two vacuum-chambers, substantially as set forth.

8. The self-acting water-elevator, consisting, essentially, of the lower vacuum-chamber, the upper vacuum-chamber connected therewith, the air-escape valves, the water inlet and outlet valves, the steam-inlets, and the tank or reservoir located beneath the upper vacuum-chamber, substantially as set forth.

In testimony whereof I have signed this specification in the presence of two subscribing witnesses.

ALFRED WILKIN.
